UNITED STATES PATENT OFFICE.

JESSE R. MOSER, OF DAYTON, OHIO.

BOMB RELEASE HANDLE.

Application filed March 5, 1925. Serial No. 13,219.

This invention relates to bomb release handles for controlling the dropping of bombs either "armed" or "safe" from aircraft.

5 One of the principal objects of the invention is to provide a release handle which, when manipulated in one plane, actuates the arming mechanism through suitable connections, and when operated in another 10 plane operates the safety mechanism, the bomber or pilot being familiar with the different manners of manipulating the handle to secure the dropping armed or safe interchangeably as desired.

15 Another object of the invention is to provide release handles to the pilot's and bomber's cockpit which are interconnected for the dual control of the dropping of bombs, so that either the pilot or bomber may 20 manipulate the handle in the event a companion is killed or disabled or is otherwise engaged.

In the appended drawings—

25 Fig. 1 is a plan view of the release handle. Fig. 2 is a side view thereof as it is mounted on or in the fuselage.

Fig. 2^a is a sectional detail taken on the line 2^a—2^a of Fig. 2, and

30 Fig. 3 is a schematic showing of the use of two interconnected release handles on an airplane.

The Army and Navy Air Service airplanes are usually equipped with bomb racks, constructed in such a way that an impulse communicated through a rod or cable will release a bomb "safe" or "armed" as desired. As determined by the position of a safety mechanism and an arming mechanism located in the bomb rack, which is operated 35 through a second rod or wire in two-place planes, it is desirable to control the bomb racks from either cockpit so that either the observer or pilot may release the bombs. Where a plane takes off with a full quota 40 of bombs, but due to some intervening cause has to land before the bombs have been dropped for destructive purposes, the bombs are dropped "safe" in order to permit the safe landing of the plane. In the event 45 either the pilot or observer should be injured or killed, his companion would have to release the bombs so that interconnected release handles for the two stations are necessary.

50 Referring to the drawing, the release handle 10 is mounted for universal pivotal move-

ment on a stud 11 about a base 12, fastened by lugs 13 or the like to the fuselage in the pilot's and bomber's cockpits, within easy reach of the pilot or bomber. The pin 14 on 60 which the handle pivots vertically passes through the stud 11 and completes a universal joint. The heel 15 of the handle overlies a lever 16 pivoted at 17 in the base 12. When the handle is swung within the direction of 65 the arrow shown in Fig. 1, the heel 15 depresses the lever 16, rotating it counter-clockwise as viewed in Fig. 2^a, thereby communicating a pull on a safety release wire or cable 18 connected on a pin 19 to the lower 70 end of the lever 16. Rotation of the release handle with the stud 11, that is on a horizontal axis in the direction of the arrow shown in Fig. 2, communicates a pull on an arming release cable or wire 20. This wire 75 is attached to a pin 21 in a bracket on the lower side of the release handle as shown in Fig. 2. The safety release wire 18 extends to a safety release mechanism 21^a in the bomb rack 22 and the arming release wire 80 20 extends to an arming release mechanism 23, also situated in the rack 22. The connections with the bomb represented at 24 are such that the pulling of the wire 18 permits the release of the bomb with its arm- 85 ing wire in place, preventing the spinner 25 from arming the firing pin in the flight of the bomb. When the wire 20 is pulled the arming mechanism 23 functions to withdraw the safety pin as the bomb is dropped, 90 so that the firing pin is armed in the operation of the spinner 25. It will not be necessary to describe in this case the safety and arming mechanism utilized, inasmuch as these are well known to the art and form 95 no part of the present invention except as to contribute to the novelty herein described.

The release handles 10^a and 10^b are shown interconnected by wires 26 and 27 attached to arms 28 and 29 respectively, extending 100 from opposite sides of the handles. The movement of either of the handles in the direction of the arrow in Fig. 2 will communicate a pull on the arming release wire 20. The safety release wire 18 is operated 105 from either of the handles 10^a or 10^b, the handle 10^a having a wire 28^a extending from its lever 16 for connection with the wire 18 intermediate the ends thereof. It is obvious 110 that the operation of either handle in the direction of the arrow of Fig. 1 will communicate a pull to the safety release wire 18.

In this way either the bomber or the pilot may release the bombs loaded in the rack.

I claim:

1. Bomb releasing means comprising a handle movable about a plurality of axes and two connections therefor with the arming and safety mechanisms of a bomb rack, whereby the operation of said handle about one axis operates said safety mechanism and the operation of said handle about the other axis operates said arming mechanism.

2. Bomb releasing means comprising in combination a plurality of handles interconnected so that one duplicates the movement of the other, and two connections therefor with the arming and safety mechanisms of a bomb rack whereby the operation of said handles one way operate said safety mechanism, and operation of said handles another way operates said arming mechanism.

3. Bomb releasing means comprising a handle, means providing a universal pivotal mount therefor, and connections for said

handle with the arming and safety mechanisms of a bomb rack whereby pivotal movement communicated to said handle in one plane operates said safety mechanism and whereby pivotal movement of said handle in another plane operates said arming mechanism.

4. In an airplane having more than one operator's position, a release handle at each position, means interconnecting said handles to operate together and arming release mechanism having connection with one of said handles.

5. In an airplane having more than one operator's position, a release handle at each position, means interconnecting said handles to operate together and arming release mechanism having connection with one of said handles, and a safety release mechanism having a separate connection with each of said handles.

In testimony whereof I affix my signature.

JESSE R. MOSER.
